UNITED STATES PATENT OFFICE.

EDWARD G. GERMER, OF ERIE, PENNSYLVANIA.

DESIGN FOR A STOVE.

Application filed December 10, 1926. Serial No. 20,011. Term of patent 3½ years.

To all whom it may concern:

Be it known that I, EDWARD G. GERMER, a citizen of the United States, residing at Erie, in the county of Erie and State of Pennsylvania, have invented a new, original, and ornamental Design for a Stove, of which the following is a specification, reference being had to the accompanying drawing, forming a part thereof, which shows a perspective view of the stove showing my new design.

I claim:—

The ornamental design for a stove as shown.

EDWARD G. GERMER.
